United States Patent Office.

PETER L. HAINS, OF FREEBURG, PENNSYLVANIA.

Letters Patent No. 96,226, dated October 26, 1869.

IMPROVED EXTENSION-SCAFFOLD.

The Schedule referred to in these Letters Patent and making part of the same.

To all whom it may concern:

Be it known that I, PETER L. HAINS, of Freeburg, in the county of Snyder, and State of Pennsylvania, have invented certain new and useful Improvements in a Painters' Extension-Scaffold; and I do hereby declare that the following is a full, clear, and exact description thereof, which will enable others skilled in the art to make and use the same, reference being had to the accompanying drawing, forming part of this specification, in which—

Figure No. 1 is a front view of said scaffold, embodying my invention.

Figure No. 2 is a side view of same, showing more particularly the arms, platform, and cog-wheels.

The nature of my invention consists in an extension-scaffold, which is intended to be used for painting-purposes, more particularly in buildings where the use of a scaffold is indispensable. By its use a painter can elevate or lower himself with great convenience, and with perfect safety, as hereinafter more fully described.

A is the foundation upon which the superstructure rests, and should be substantially constructed.

b exhibits the upright shafts, in which the platform *d*, upon which the painter stands, is elevated, by means of the rope *n*, passing through pulley *i*, and winding on the windlass *e*. The arms *c*, (and *l* in the extension,) rest against the building, keeping the scaffold perpendicular; the pressure of weight being toward the building, keeping the centre of gravity between the building and base of scaffold; the arms *c* also serving to bind the top of upright shafts.

The rope *m* passes through three pulleys, *f* *g* *h*, and winds on windlass *k*, and is used in elevating the platform *d* in the extension *j*; which commences at arms *c*.

Having thus fully described my invention, What I claim, and desire to secure by Letters Patent, is—

The upright shafts *b*, extension *j*, pulleys, *i*, *h*, *g*, and *f*, ropes *m* and *n*, and platform *d*, all constructed, arranged, and operating substantially as herein described, and for the purpose set forth.

PETER L. HAINS.
